The ornamental design for a mobile hologram apparatus, as
shown and described.

DESCRIPTION

FIG. 1 illustrates a perspective view of an unfolded assembled mobile hologram apparatus, according to a first embodiment.

FIG. 2 illustrates a top plan view of the unfolded assembled mobile hologram apparatus showing side 1, side 2, side 3, and side 4, according to the first embodiment.

FIG. 3 illustrates a view of side 1 of the unfolded assembled mobile hologram apparatus, according to the first embodiment.

FIG. 4 illustrates a view of side 3 of the unfolded assembled mobile hologram apparatus, according to the first embodiment.

FIG. 5 illustrates a bottom plan view of the unfolded assembled mobile hologram apparatus, according to the first embodiment.

FIG. 6 illustrates a view of side 2 of the unfolded assembled mobile hologram apparatus, according to the first embodiment.

FIG. 7 illustrates a view of side 4 of the unfolded assembled mobile hologram apparatus, according to the first embodiment.

FIG. 8 illustrates a top perspective view of an unfolded assembled mobile hologram apparatus, according to a second embodiment.

FIG. 9 illustrates a plan view of the unfolded assembled mobile hologram apparatus showing side 1, side 2, side 3, and side 4, according to the second embodiment.

FIG. 10 illustrates a view of side 1 of the unfolded assembled mobile hologram apparatus, according to the second embodiment.

FIG. 11 illustrates a view of side 3 of the unfolded assembled mobile hologram apparatus, according to the second embodiment.

FIG. 12 illustrates a bottom plan view of the unfolded assembled mobile hologram apparatus, according to the second embodiment.

(Continued)

FIG. 13 illustrates a view of side 2 of the unfolded assembled mobile hologram apparatus, according to the second embodiment; and,

FIG. 14 illustrates a view of side 4 of the unfolded assembled mobile hologram apparatus, according to the second embodiment.

In the drawings, the broken lines depict environmental subject matter only and form no part of the claimed design. Additionally, the mobile hologram apparatus is not limited to the scale shown herein.
